UNITED STATES PATENT OFFICE.

FRED RICKS, OF LEICESTER, ENGLAND, ASSIGNOR TO UNITED SHOE MACHINERY CORPORATION, OF PATERSON, NEW JERSEY, A CORPORATION OF NEW JERSEY.

MACHINE FOR OPERATING UPON PIECES OF STOCK.

Application filed November 13, 1924, Serial No. 749,733, and in Great Britain December 21, 1923.

This invention relates to improvements in machines for operating upon pieces of stock and is herein illustrated as embodied in a machine for operating upon boot or shoe soles before the soles are attached to boots or shoes.

In the practice of the usual methods of shoe manufacture various operations are performed in which the margin of the sole of a shoe is engaged by a wheel which is usually serrated so as positively to feed the work while the work is manually guided past an operating tool or tools located approximately at the point of bite of the wheel on the work. One of the most used operations of the above nature is that of channeling a sole for the reception of a line of stitching which is subsequently made in the sole and an example of a sole channeling machine is that shown in United States Letters Patent No. 1,004,614, granted October 3, 1911, upon application of H. W. Winter. Machines of this nature are generally provided with a serrated feed wheel of considerable width and, as shown and described in the patent referred to, the serrated wheel is sometimes composed of a plurality of toothed disks between which relative movement may take place as the work passes along in order to prevent undue tearing of the work surface when the sole is swung for the purpose of progressively presenting the curved portions of its margin to the operating tool. It has been found, however, that even though the disk composing the toothed feed wheel are permitted to move relatively to each other as above described more or less undesirable tearing or defacing of the work surface results from the inevitable movement of the zone of the work engaged by the serrated wheel in a direction across the surface of the wheel as the work emerges from the operating point whenever a curved portion of the sole margin is being operated upon.

In view of the foregoing, one object of this invention is to avoid undesirable tearing or defacing of the work such as that above adverted to.

To this end, one feature of the present invention consists in the provision, in a machine for operating upon pieces of stock, of a toothed work indenting feed wheel and unyielding means constructed and arranged to engage the portion of the work in which the teeth of the feed wheel are indented positively to strip the stock from the feed wheel.

In the embodiment of the invention herein shown, a channeling machine is provided with co-operating feed wheels, one of which comprises a plurality of parallel work-indenting surfaces or toothed feeding sections, and a main guard member, arranged partially to encircle said work-indenting surfaces, is formed with projections arranged to enter between such surfaces to hold the sole out of contact therewith immediately the sole has passed beyond the common axial plane of the feed wheels.

In the illustrated embodiment of the invention, the main guard member is rigidly secured at its lower end to the frame of the channeling machine while the upper extremity of the guard member, which is effective to part the work from the teeth of the feed wheel, is unsecured to the frame. In order to prevent the stock from pressing the upper extremity of the main guard member downwardly against the teeth of the feed wheel so as to interfere with the rotation of the wheel, the illustrated machine is provided with a support for the free extremity of the guard arranged to partake of the rotary movement of the feed wheel. As shown, this support for the guard is in the form of a disk adjacent to and coaxial with the toothed feed wheel and having a smooth periphery adapted to engage and support the guard.

In order to insure against possibility of the work being unduly marked or defaced by the teeth of the lower feed wheel before the work reaches the bite of the feed wheel, the illustrated machine is provided with a work-indenting feed wheel, and a guard member adapted to limit engagement of the work with the wheel before the work reaches the operating point. This last-mentioned guard member is herein illustrated as partially encircling the outer feeding section of the lower feed wheel and having a free extremity overlying and capable of being supported by the guard which parts the work from the feed wheel.

The above and other objects and features of the invention will become apparent upon consideration of the following description of the illustrative device shown in the accompanying drawings, in which:

Fig. 1 is a front elevational view showing the work feeding and pressing wheels of a machine of the general type disclosed in the patent above referred to, together with guard

members constructed in accordance with the present invention; and

Fig. 2 is a plan view of the parts below the line 2—2 of Fig. 1.

Referring to the drawings, all parts of the machine, with the exception of those hereinafter specifically described, may be of the general type disposed in the patent hereinbefore mentioned, and the lower feed wheel 4, which is a serrated feeding member, may also be of the general nature indicated in said patent. As shown, the lower feed wheel 4 consists of a plurality of disks 6, 8 and 10 severally comprising annular feeding sections having teeth on their outer peripheries of less width than the thickness of the disks. Co-operating with the lower feed wheel 4 is an upper feed wheel 12. A channel knife is indicated at 14 and a rotatable edge gage at 15, the channel knife being arranged to cut the work at a point in the common axial plane of the feed wheels and the edge gage functioning in the usual manner to locate the work relatively to the feed wheels and the channel knife. All of the annular feeding sections comprising the lower feed wheel are provided with ball clutches (not shown) which may be of the type disclosed in said patent and by means of which the feeding sections are connected with a driving shaft 16 so that they are positively driven by the shaft but are free to be turned forwardly thereon by the work. The disk 10, which is located nearest to the margin of the work, is thicker than the other disks and has one portion 18 of its periphery smooth while the other portion thereof is serrated. Adjacent to the disk 10 are the two relatively thin serrated disks 8 and 6, the annular feeding sections of which are rotatable independently of each other and of the disk 10 by reason of the ball clutch mountings above referred to. A fourth disk 20 is arranged adjacent to the disk 6, and is positively connected to the driving shaft 16. The disk 20 has no teeth upon its periphery and is of a diameter approximately equal to that of the circle of the bottoms of the teeth on the other disks.

The means for parting the work from the lower feed wheel comprises a guard 22 which is arranged to cover the whole width of the lower feed wheel at that side on which the work emerges from the bite of the wheels. The guard 22 may conveniently be made in two parts 23 and 24 secured together by screws 25 and the part 24 may be rigidly secured by means of screws 26 to a fixed portion of the frame of the machine. The portion 23 of the feed wheel guard is provided with an approximately horizontal and smooth upper surface the leading edge of which is located approximately at the common axial plane of the upper and lower feed wheels. The portion 23 of the guard 22 is further provided with small projections 30

which enter and fit closely within the spaces between the rows of teeth upon feeding sections of the lower feed wheel. Viewed axially of the feed wheel shaft 16 the teeth 30 taper to points at their leading edges, these points being located in the circle of the bottoms of the teeth on the disks. 70

A second stationary work guard or guide 32 is located over the disk 20 and is arranged closely to surround the upper quarter of said disk on the side at which the work enters the grip of the feed wheels. As shown, the guard 32 is secured by screws 34 to a fixed portion of the frame of the machine. The thickness of the guard 32 is substantially equal to the 80 height of the teeth on the disks 6, 8 and 10 and provides a smooth work-engaging and supporting surface of the same curvature as the circle of the outer extremities of the teeth. This guard 32 also tapers at its free 85 extremity, as indicated at 36, the tapered portion being located substantially at the bite of the feed wheels. The tapered extremity of the guard 32 overlies and is supported by the most advanced portion of the first- 90 mentioned guard 22, as clearly shown in the drawings.

The function of the guard 22 is to lift the work from the teeth of the lower feed wheel as the work passes the operating point, i. e., 95 the point in the common axial plane of the feed wheels at which the work receives maximum pressure from the feed wheels. Thus, when a convexly curved portion of the sole 100 margin is being operated upon and the sole is manually swung, as may be necessary progressively to maintain its curved margin in position to be operated upon, the inner portion of the zone of the work engaged by the teeth of the lower feed wheel will be parted 105 or stripped from the teeth immediately the sole leaves the point where it receives its greatest pressure from the feed wheels. The work therefore cannot be damaged by the teeth of the lower feed wheel since the 110 work is not permitted to be moved in a direction across the surface of the wheel after leaving the point of greatest feeding pressure at the bite of the feed wheels.

Under working conditions the free extremity of the main guard 22 is adapted to be supported by engagement with the periphery of the disk 20. In the absence of such a support, pressure upon the guard 22 by, for example, the thicker grades of work, might result in actual contact of the guard 22 with the ball-clutch driven disks, with the consequent prevention of the desired action of the clutches at times when curved portions of the sole would normally cause said disks to move 120 in advance of the other operating parts.

Inasmuch as the second guard or guide 32 rests upon the main guard 22, which is unyieldingly supported under working conditions, the guard 32 is likewise unyieldingly 125

supported and it serves to support the work in such a manner that the work cannot be pressed downwardly into too deep engagement with the teeth of the toothed disk 6 before the work reaches the operating point. Consequently, the guard 32 functions to prevent the work from being unnecessarily injured by the teeth of the feed wheel as the work is turned.

10 As is usual in this class of machines, a plurality of strippers 38 has been provided, these strippers acting in the grooves between adjacent disks of the lower feed wheel to remove from the wheel any particles of leather or dirt which may adhere to it.

The invention having been described, what I claim as new and desire to secure by Letters Patent of the United States is:—

1. In a machine for operating upon pieces of stock, in combination, a toothed work indenting feed wheel, and unyielding means constructed and arranged to engage the portion of the work in which the teeth of the feed wheel are embedded positively to strip the stock from the feed wheel.

2. In a machine for operating upon pieces of stock, in combination, a feed wheel arranged to exert feeding pressure upon the stock, and an unyielding feed wheel guard partially encircling the feed wheel for parting the stock from the feed wheel, said guard being constructed and arranged to begin its parting action at the point at which the feed wheel exerts its maximum pressure upon the stock.

3. In a machine for operating upon pieces of stock, in combination, a feed wheel arranged to exert feeding pressure upon the stock, a feed wheel guard partially encircling the feed wheel for parting the stock from the feed wheel immediately after it has passed the point at which the feed wheel exerts its maximum pressure upon the stock, rigid means for supporting the guard at a point removed from its operative extremity, and means upon the feed wheel for supporting the operative extremity of the guard.

4. In a machine for operating upon pieces of stock, in combination, a feed wheel arranged to exert feeding pressure upon the stock, a feed wheel guard partially encircling the feed wheel for parting the stock from the feed wheel immediately after it has passed the point at which the feed wheel exerts its maximum pressure upon the stock, rigid means for supporting the guard at a point removed from its operative extremity, and an annular flange formed upon the side of the feed wheel for supporting the operative extremity of the guard.

5. In a machine for operating upon pieces of stock, in combination, a feed wheel for feeding the stock, a feed wheel guard partially encircling the feed wheel for parting the stock from the feed wheel immediately

after the stock leaves the point of bite of the wheel upon the stock, and a second guard partially encircling the feed wheel throughout a portion of the width of the latter for limiting the engagement of the stock with the feed wheel before reaching said point, the operative extremity of the first guard underlying the second guard and being adapted to support the latter.

6. In a machine for operating upon soles for boots and shoes, in combination, co-operating feed wheels between which the soles are fed, work indenting teeth on one of said wheels, an unyielding member extending to the common axial plane of the feed wheels and constructed and arranged to part the work from the toothed wheel immediately after the work has passed beyond said common axial plane.

7. In a machine for operating progressively along the margin of a sole, the combination with a feed wheel having a plurality of parallel work-indenting surfaces, of a work guard partially covering the work indenting surfaces of the feed wheel and provided with projections entering between said surfaces and arranged to part the work from the feed wheel immediately after the work has passed the operating point.

8. In a machine for operating progressively along the margin of a sole, a work supporting lower feed wheel, an upper feed wheel arranged to apply downward pressure to work supported by the lower feed wheel, a guard arranged to protect the work engaging portion of the lower feed wheel, and means on the lower feed wheel for supporting the guard against the downward pressure of the upper feed wheel.

9. In a machine for operating progressively along the edge of a sole, a toothed feed wheel for engaging one face of the sole, means coacting with the feed wheel to hold the sole in engagement therewith, a member partially encircling the feed wheel and having a free extremity constructed and arranged to strip the work from the feed wheel immediately after the work passes the point at which the feed wheel is most effective to feed the work, and means on the feed wheel for supporting the free extremity of said member.

10. In a machine for operating progressively along the margin of a sole, co-operating feed wheels arranged to engage opposite sides of a sole and to feed the sole, one of said wheels comprising a plurality of parallel work-indenting surfaces, and a feed wheel guard arranged to cover a portion of said surfaces and provided with a plurality of projections arranged to enter between said work-indenting surfaces and to strip the work therefrom immediately after the work has passed the point of maximum pressure at the bite of the feed rolls.

11. In a machine for operating progressively upon the margin of a sole, in combination, an operating instrumentality, a work indenting feed wheel, a guard for parting the work from the feed wheel after the work has passed the operating instrumentality, a disk of smaller diameter than the feed wheel and arranged beside the latter for supporting said guard under working conditions, and a second guard partially encircling the periphery of said disk and constructed and arranged to limit engagement of the work with the feed wheel before the work reaches the operating instrumentality, said second guard being supported by engagement with said first guard.
12. In a channeling machine, the combination with a lower feed wheel comprising a plurality of parallel toothed feeding sections, of an upper feed wheel co-operating with the lower feed wheel to feed the work, a guard partially encircling said feeding sections, and a plurality of fingers at one extremity ²⁰ of the guard extending between said feeding sections for parting the work from the feed wheel immediately the work passes the common axial plane of said feed wheels.

In testimony whereof I have signed my name to this specification.

FRED RICKS.
